Filed Oct. 20, 1965, Ser. No. 87,647

Term of patent 14 years

(Cl. D48—20)

FIG. 2 is a top view of the flashlight holder.

FIG. 3 is a fragmentary cross-sectional view of the flashlight holder taken along the line 3—3 of FIG. 2, the general configuration of the internal cavity being shown in broken lines.

FIG. 4 is a side elevational view of the flashlight holder as viewed from the left in FIG. 1.

The dominant features of our design reside in the portions shown in full lines.

We claim:

The ornamental design for a flashlight holder, substantially as shown and described.
